UNITED STATES PATENT OFFICE.

ALBERT J. HAUSKAMA, OF BUTTE, MONTANA.

TACK HOLDER.

1,403,408.

Specification of Letters Patent. Patented Jan. 10, 1922.

Application filed July 14, 1921. Serial No. 424,673.

To all whom it may concern:

Be it known that ALBERT J. HAUSKAMA, a citizen of the United States of America, residing at Butte, in the county of Silver bow and State of Montana, has invented 5 new and useful Improvements in Tack Holders, of which the following is a specification.

The object of the invention is to provide 10 a simple, inexpensive and efficient tack holding device adapted for facilitating the manual holding of a tack during the starting or driving thereof and designed to be of such a moderate cost as to permit of 15 including a specimen of the same in each box of tacks sold for domestic use; and with this object in view the invention consists in a construction and combination of parts of which a preferred embodiment is 20 shown in the accompanying drawings, wherein:

Figure 1 is a view of a tack holder constructed in accordance with the invention as seen when in actual service.

25 Figure 2 is a detail plan view of the same.

The device consists essentially of a shank 10 provided at one end with a handle or finger hold 11 which may be of looped 20 form as shown and provided at the other end with an open loop 12 formed by doubling the extremity of the shank upon itself to provide a means for engaging the stem of a tack indicated at 13, so that the 30 latter may be held in proper position for striking the head with a hammer without exposing the fingers of the operator to the impact of the latter.

The tack holding element of the device, 40 or the portion of the wire constituting the

said element is preferably flattened to increase its resilience and its bearing surface on the shank of the tack so as to more effectively hold the latter in proper position during the setting of the tack in the floor, 45 and the extremity of the tongue 14 representing the free side of the tack holding element being yieldingly held in contact with the shank may readily be displaced after the point of the tack has been set in 50 the floor, to permit of the disengagement of the holder from the tack so that the final driving of the latter may be effected without injury to the holder.

It will be noted that the device is made 55 from a single blank of wire which should be of steel or like material having sufficient resilience to cause the tack engaging element thereof to properly clamp the stem or shank of the tack so that the latter may be 60 held firmly in position during the driving operation or until the point of the tack has been substantially seated in the wood work.

Having described the invention, what is 65 claimed as new and useful is:—

A tack holder constructed of a single blank of wire having a shank provided at one end with a handle and longitudinally flattened at the other end, the flattened end of the shank being bent back on itself to 70 provide a loop of which the free arm is yieldingly impelled toward the stationary arm, the extremity of the free arm being deflected from the fixed portion of the clamp to permit the ready insertion of a tack between the arms of the loop as herein shown and for the purpose specified.

In testimony whereof he affixes his signature.

ALBERT J. HAUSKAMA.
